UNITED STATES PATENT OFFICE

DONALD B. McDONALD, OF QUITMAN, GEORGIA

BARREL-HEAD-FASTENING MEANS

Application filed March 19, 1929. Serial No. 348,298.

This invention relates to certain new and useful barrel head fastening means and is intended to overcome certain difficulties encountered in devices of this character as, for example, is shown in the patent to Mote et al 1,197,387, September 5, 1916. In devices of this character it is desirable that when the barrel or receptacle is turned down that such semi-fluid contents as rosin etc. will readily flow out if the barrel head is removed. In the device described in the patent the rim 5 would obstruct the outflow of the material and it is one object of the applicant's invention to provide a rim that will extend only a little distance inwardly from the usual groove nearest the end of the barrel and which would be more or less flexible so that it could be easily inserted in the groove.

Another object of applicant's invention is to cheapen and simplify the construction of the barrel head fastening means while at the same time making it easy to operate.

Another object of the invention is to provide a wedging fit between the barrel head and staves and the fastening means are more or less elastic to take up any wear between the periphery of the barrel head and the staves. With these and other objects in view which will be developed as the description proceeds I will now describe my invention in connection with the accompanying drawings in which,

Figure 1 is a top plan view of my invention with the head partly broken away to disclose the clamping means.

Figure 2 is a fragmentary section on the line 2—2 of Figure 1.

Figure 3 is a bottom view of the barrel head detached.

Figure 4 is a view of my improved holding ring.

Figure 5 is a section in perspective of the ring clamping offset.

Figure 6 is a perspective of a bar beneath the head with the wedge shaped ends that cooperate with the ring offsets.

1 is the head which, as shown in Figure 2, fits snugly into the end of the barrel 2 and to the head 1 I bolt a bar 3. This bar extends above the barrel sufficiently to act as a handle

to be clasped and the head given a turning motion after the ends 5—5 of a bar 4 have been started under the offsets 6—6 formed integral with a ring 7. The offsets 6—6 are preferably slightly springy in their action and may be inclined to the plane of the ring as shown in Figure 2 although such inclination is not necessary.

The bolts 9—9 extend through the bar 3 on top of the head through the head 1 and the bar 4 as best shown in Figure 2.

The bar 4 may also be somewhat springy to take up any wear between the head and top of the barrel staves. It will be observed that when the barrel head is removed and the barrel turned down the ring offers little or no obstruction to the outflow of material from the barrel and the ring may be left in the barrel after having been once inserted therein.

It will be observed that by my construction while the head preferably rests on the ring the barrel head need not rest directly on the ring but some distance above the ring and as the periphery of the head wears or the inner portions of the ends of the staves become worn the head may still be held tightly in the end of the barrel by my fastening means.

When the head is inserted in the end of the barrel and the wedge shaped ends 5 of the bar 4 comes against the lower edge of the offset 6 as the head is turned slightly it will tighten the parts and make a tight fit between the periphery of the head and the staves or the head and ring even though these parts become more or less worn or displaced.

The operation of my clamping means is apparent from the foregoing but to summarize the same the ring 7 is placed in the barrel groove and the barrel head inserted in the upper end of the barrel which is preferably larger at the extreme end of the barrel than it is farther down at or near the ring 7. Having first placed the head in the open ended barrel it is turned until the wedge shaped ends 5 catch on the offsets 6 of the ring 7 and pull the head downwardly into the end of the barrel and ordinarily rests on the ring and by reason of the wedge shaped ends 5 cooperating with the offsets 6

and the barrel head may thus be firmly held

to the barrel to stand any reasonable internal pressure. It is apparent that instead of having the barrel end slightly tapering the head may be tapered slightly so as to maintain the fit between the periphery of the head and the open end of the barrel.

Having thus described my invention what I claim is:

1. A container head fastening means comprising a container having an internal groove near its end, an elastic ring fitting into the groove and substantially enclosed in the groove said ring having offsets extending inwardly from the groove and a head fitting snugly into the end of the container above the rim said head having attached thereto on its underside a bar with wedge shaped ends approximately at the outer periphery of the underside of the head and adapted to cooperate with the offsets on the rim to pull the head into the end of the container and tighten the fit between the head and the interior of the container.

2. A container having a groove near its end, a ring adapted to fit in said groove and to be substantially enclosed therein said ring having diametrically oppositely disposed offsets extending inwardly from said ring and in substantially the same plane as the ring and a head for the container having on its inner surface a bar with wedge shaped ends extending circumferentially of the head and terminating at approximately the outer periphery of the head.

35 In testimony whereof I affix my signature.
DONALD B. McDONALD.
